BRAKE

Theron P. Chase, Detroit, Mich., assignor to General Motors Corporation, Detroit, Mich., a corporation of Delaware

Application September 16, 1939, Serial No. 295,205

4 Claims. (CL 188—152)

This invention relates to friction brakes and is the result of efforts to improve a brake of the kind having an assembly of shoes adapted to be spread into engagement with the flange of a rotating drum.

The object of the invention is to provide a shoe assembly such that each shoe is self-energized by the drum for each direction of rotation whereby the greatest possible advantage may be taken of the energizing effect of the rotating drum thereby minimizing the manual effort required to apply the brakes; so to arrange the spreading and anchoring mechanism that the effective braking action of the shoes shall be substantially equalized for each direction of drum rotation to the end of equalizing the wear of the friction facings and to avoid drum distortion; and to produce this equalized action by a servo effect of one shoe upon the other in each direction of drum rotation without the need for a duplication of applying means whereby the construction may be comparatively simple and inexpensive.

As another object the invention aims to accomplish the major object with shoes so constructed as to employ the well-known articulating link anchorage.

The accompanying drawings show embodiments of the invention.

In the drawings:

Figure 1 is a transverse section through the flange of a drum showing the shoe assembly in elevation.

Figure 2 is a section on line 2—2 of Fig. 1.

Figure 3 is a section on 3—3 Figure 1.

Figure 4 is a view in elevation as seen from line 4—4 of Figure 3.

Figure 5 is a section on line 5—5 of Figure 1.

Figure 6 is a section on line 6—6 of Figure 1.

Figure 7 is a transverse section through the lower part of a drum flange showing a modified form.

Figure 8 is a section on line 8—8 of Figure 7.

Figure 9 is a transverse section through the lower part of the flange of a drum showing another modification.

Figure 10 is a section on line 10—10 of Figure 9.

Figure 11 is a transverse section through the upper part of the flange of a drum showing a modified form.

Figure 12 is a section on line 12—12 of Figure 11.

Referring to Figures 1 to 6, numeral 11 is used to designate a brake drum. It will be understood that in the environment for which the invention is more particularly intended, one such drum will be carried by each vehicle wheel. Mounted ad-

5 jacent the drum but not for rotation is a cover plate 13 which also serves as the medium through which the brake torque from the shoes is transmitted to the rear axle housing or to the front steering knuckle as the case may be. There may be a torque plate 15 between the bottom of the drum and the drum cover as shown in Figures 1 and 3. When such a torque plate is used it takes the torque directly and, being fastened to the cover at 17, transmits the torque to the cover.

As shown on the drawings there are two shoes 19 and 21 having webs 19' and 21' and flanges provided with friction facings 23 to engage the flange of the drum as usual.

10 The objects of this invention are attained by the use of a single motor unit. This is marked 25 and is secured to the cover between one pair of adjacent ends of the shoes. The motor unit shown is the so-called wheel cylinder of a conventional hydraulic system. It includes a cylinder 27, two pistons 29 and 29' each provided with a sealing cup 31. Fluid from the master cylinder is admitted to the space between the two pistons. Between the two pistons is a spring 33 to hold the cups 31 against the pistons. At one end of the cylinder, piston 29 engages a disk 35 which is adapted to engage the cylinder end. The disk has a notched guiding flange 37 embracing the cylinder. Threaded to the disk 35 is a plunger 39 having a forked end engaging the web 19'. The other piston 29' has a socket 41 to receive the rounded end 43 of a link 45 pivoted to shoe 21 at 47. The link is formed from two plates 45' and 45'' of which plate 45'' continues beyond the pivot 47 and carries a pin 49 extending through a somewhat enlarged opening 51 in the web 21'. A spring 53 surrounds the pin and presses the plate 45'' frictionally against the web 21'. By this construction the angular relation between the shoe and the link 45 may vary to obtain the most effective frictional engagement between the shoe and the drum flange without the occurrence of undesired rotation of the links at 47. A spring 55 is terminally connected to the shoes 19 and 21 to bias the assembly to its released position. Other springs 57 and 59 connect the shoes to the torque plate, these springs being located near the other pair of shoe ends. It will be noted that by the rotation of disk 35 adjustment is provided to

50 accommodate the lining wear of shoe 19. The disk 35 by its engagement with the end of cylinder 27 limits the release movement of the shoe toward the cylinder whereby the cylinder becomes a torque receiving abutment. In a similar way piston 29' has an annular flange 29'' which may

engage the end of cylinder 27 for a like purpose.

Torque plate 15 has three elongated openings in the region adjacent the pair of shoe ends remote from cylinder 27. These are radially spaced and are marked 61, 63 and 65 respectively. A pin 67 extends through opening 61. On the sides of torque plate 15 are links 68, 68' supported on pin 67. Rotatably supported by links 68, 68' are pins 71 and 73 which pass through torque plate openings 63 and 65 respectively. Other links 75, 75' are supported on pin 67. These links 75, 75' overlie the ends of pin 71 but are received on reduced ends 73' of pin 73. Each of the links 75, 75' has upper and lower flaring slots 77 and 79, the registering slots 77 opening toward shoe 19 while the slots 79 open toward shoe 21. Retainer plates 81, 81' are also carried by pins 67 and 73. These plates cover the slots and are held in place by the heads of the pins and by fastening means such as snap rings 83. The several links and plates constitute a lever operable for a purpose to be explained.

A pair of plates 85, 85' form an articulating link for shoe 19. These plates lie on opposite sides of the web of the shoe and are pivoted thereto by a pin 87. Near the end of the shoe is a spring device comprising a spring 89 surrounding a pin 91, the device functioning to permit a limited swinging of the linkage resisted by friction between the web and the linkage. The ends of link 85 and 85' are tapered and seat in the flared slots 77 as best shown by Figure 4. Similarly seated in slots 79 are the furcations of a thrust member 92. A stem 93 is seated in an opening of member 92. It is provided with a notched annulus 95 and its other end is threaded to engage a threaded opening 97 in a link 99 pivoted to the web 21' of shoe 21 at 101.

When the vehicle is at rest and the brake not applied, the springs 85, 87 and 89 hold the shoes away from the drum. Disk 35 and flange 29' determine the release position at the wheel cylinder end of the shoes and the end walls of slots 63 and 65 determine the corresponding position at the other ends of the shoes. The forces exerted by spring 87 and 89 are applied to the floating link means 75 and 75' constitute a couple to hold the parts in the position shown in Figure 1. If the brake is applied while the vehicle is standing the linkage 85, 85' for one shoe and 92 for the other constitute the anchoring means and the two shoes are spread apart each being equally effective to hold the car against rolling. If on the other hand the vehicle is moving and the drum rotating counterclockwise (Figure 1) the pressure applied at 39 to shoe 19 is supplemented by the self-energizing effect upon shoe 19 of the rotating drum. The engagement of pin 71 with the wall of the slot 63 takes one part of the force so applied but since the force so applied to the link is a short distance from the axis of pin 71 the link is free to turn and apply a force to the end of link 92 and to the shoe 21. The leverage is so chosen that the part of the force which is applied to shoe 21 when supplemented by the self-energizing force applied by the drum to shoe 21 causes the braking effect of the two shoes to be substantially equal. In this way the whole drum arc is used and the required pedal pressure is reduced to a minimum. In the case of reverse drum rotation the effect is substantially the same. A part of the pressure of the energized shoe 21 is anchored by pin 73 engaging the end of slot 65 and a part acts as a servo force to apply shoe 19 which,

when so applied, is additionally energized by the rotating drum. This reversibility in action is made possible by the floating support of the lever between the shoes. The specific structure 5 of this lever is of importance. If the articulating links at the ends of the shoes were to engage the links 75 and 75' at distances from the adjacent pins greater than the radius of these pins the pins would obviously need a greater spacing than in the arrangement shown to obtain the desired leverage. By the arrangement illustrated it is possible to secure the desired ratio of lever arms with a lever not too great in length to be installed in the conventional brake. It will be seen from Figure 3 and Figure 4 that the linkage 85, 85' straddles the end of pin 71 and that its axis intersects the linkage at a distance from the center of pin 71 less than the radius thereof. This is made possible by the association of links 68 and 75. In the case of linkage 92 the forks also engage links 75, 75' but engage the links in the plane of the reduced parts 73' of the pin 73 and in this case, the same relation prevails relative to the radius of the pin 73.

In Figures 7 and 8 is shown a second and simplified form which, being simpler, may be regarded as a preferred embodiment. In these figures the drum is marked 111 and numerals 119 and 121 designate the shoes. The backing plate 113 is formed as shown in Figure 8 and an anchor plate 115 at its lower end is shaped as shown by Figure 7. An angular plate 117 is welded to the cover plate 113. It has an axial flange 119 provided with an elongated opening 121. The opening has one marginal wall bent up as at 123. A pivot pin 125 is mounted in the cover plate 113 and the lower portion of the anchor plate 115. A lever 127 has an elongated slot 129 surrounding pin 125. The lever has its lower end projecting into slot 121 and normally engages the surface 123. Near the lower end of the lever is a thrust pin 131 carried thereby and engaged on the sides of the lever by links 133, 135, which together are pivoted to shoe 119 at 137. At 139 there is provided an expedient corresponding to the construction shown in Figure 5. Near pivot pin 125 the lever 127 is notched as at 141 on the side adjacent shoe 121 and the walls of the notch are engaged by the furcations at the end of a link 143. The link includes an internally threaded socket 145, a stem 147 threaded therein, the stem having a notched ring 149 and a smooth surface extension 151. The stem 147 is rotatably supported in a socket 153 having the bifurcated end embracing the web of shoe 121. Springs 155 and 157 are attached to the shoes and to the anchor plate 115 to hold the shoes in their brake released position. It will be understood that the shoes are expanded by means at their opposite pair of adjacent ends as in Figure 1. In this form of the invention, counterclockwise drum rotation causes the drum to supplement the pressure applied to shoe 119. The force derived from the wheel cylinder and the self-energization is transmitted by the shoe in part to the abutment 123 and in part is transmitted to the secondary shoe through the instrumentality of the link 143. The force transmitted to the secondary shoe is supplemented by the self-energizing effect of the drum, the secondary shoe anchoring as in Figure 1 at the end of the wheel cylinder or upon some other convenient anchorage, and using preferably the well-known articulating link. Thus by the use of the articulating linkage, both shoes accommo-

date themselves to the outline of the drum exerting a maximum force at the mid-points of their arcs. Also each shoe is self-energizing due to the presence of the anchorage for each and the resistance offered to drum rotation is substantially the same in the case of each shoe, this being accomplished by properly determining the lengths of the arms of lever 127. Upon reverse rotation of the drum the brake operates in substantially the same way. It will be seen that this embodiment of the invention so spaces the fulcra 123 and 125 that it becomes unnecessary to resort to the expedient shown by Figure 1 where the ends of pin 71 are overlapped by the articulating links 85, 85'. The construction is thus greatly simplified.

Figures 9 and 10 show a similar but slightly different form. In this embodiment numeral 211 is used to designate the drum and 213 the cover. The anchor plate is made up of two laminæ 215, 215' in close contact with each other in the region where they are secured to the cover but spaced at the lower end of the drum where they straddle the lever 217. A spacer 219 is secured by fastening means 221 between the extremities of plates 215 and 215' and this spacer is formed with an elongated slot 223 which receives the end of lever 217. At its upper end the lever has an elongated slot 225 embracing a pin 227 supported by the laminæ 215, 215'. The lever 217 is formed on its opposite faces with recesses, one near the lower end and the other near the upper end. The recesses receive the ends of adjustable links 229 and 231 connected to the shoes 233 and 235. Springs 237, 239 connect the shoes to the anchor plate and bias the parts to the position shown in Figure 9. Each articulating link is composed of three parts, a shoe engaging part 241 having a bifurcated end and a pivot pin 243, a stem 245 having one end unthreaded and received within a pocket of part 241 and a threaded end adjustably received with the third part, a socket 249, which is seated, as stated above, in a recess of the lever. The operation of the parts described will be understood from the description of the embodiment illustrated in Figure 7.

It will be observed that in Figure 9 there is an adjustment in each of the shoe articulating links 229 and 231, this arrangement differing from the embodiment shown in Figure 7 in which but one of the articulating links is made adjustable. When the articulating link for one shoe only is adjustable a second adjustment is provided for the other shoe at its end remote from the adjustment for the first shoe. This construction is shown in Figure 1, the second adjustment being seen at 39. The construction shown by Figure 9 provides another use for the laminated anchor plate. Where, as in Figure 1, the ends of the wheel cylinder take the brake torque, the cylinder must necessarily be quite rigid. It is possible to make a wheel cylinder of sheet metal insofar as its function of applying the brake is concerned, especially in a brake where the applied force may be low as in the present brake where self-energization is used to supplement the applied force.

In Figures 11 and 12 there has been shown a sheet metal wheel cylinder together with an anchorage for the shoes independent of the cylinder. The anchorage is seen to be a pin 251

carried by the spaced upper ends 253, 253' of the anchor plates. By this construction the thrust of one or the other of the brake shoes is transmitted directly to the pin 251 and is not transmitted to the ends of the cylinder. It is therefore possible to make the cylinder of light weight material. Inasmuch as the cylinder does not receive the brake torque a simplified form for its support is made possible. The plates 253 and 253' are cut out as at 255 and on either side of the opening so formed the plates are bowed away from each other to form cooperating pockets 257 and 259 within which the sheet metal cylinder 261 is mounted. This cylinder carries pistons 263 and plungers 265 as before. Within the opening 255 the cylinder is embraced by a block 267. The block has an opening 269 registering with an opening in the cylinder and also communicating with a conduit 271 from the master cylinder. A bleed plug is shown at 273. The pin 251 is formed with an axial extension 275 to which the ends of springs 275' and 277 are connected, the other ends of these springs being connected to the shoes. By this means the shoes 279 and 281 are normally held in contact with the anchor pin 251. While this arrangement for supporting the cylinder and providing the adjacent anchor pin for the shoes may be used with other arrangements at the opposite ends of the shoes it is particularly useful with an arrangement corresponding to that of Figure 9 since that form makes use of a two-part anchor plate.

I claim:

1. In a brake, a drum, a pair of shoes frictionally to engage the drum, spreading means between one pair of adjacent shoe ends, mechanism to anchor and connect said other pair of shoe ends whereby each shoe is adapted to act directly as a self-energizing shoe and also to act as a servo device to actuate the other shoe, said mechanism comprising a lever positioned between the second pair of adjacent ends, two pivot members about either of which said lever may rotate, a link pivoted to each shoe, said links engaging said lever, one near each pivot member and at a distance from the axis of said pivot member less than the radius thereof.

2. In a brake, a drum, a pair of shoes, a fixed anchor spreading means between one pair of shoe ends, said anchorage having radially spaced slots, first and second pins in said slots, a lever including first links rotatably mounted on said pins, one on each side of the anchorage, second links overlying said first links and the ends of one of said pins, said second links being rotatably supported on reduced ends of the other of said pins, other pin and slot connections between said first and second links and the anchorage, said second links having oppositely directed slots between said first and second pins, and articulating links pivoted to said shoes and engaging in said slots.

3. The invention defined by claim 2, the articulating links engaging said second links each at a distance from the axis of the adjacent pin less than the radius of said pin.

4. The invention defined by claim 2, together with retainer links mounted alongside said second links to close the slots therein.

HERON F. CHASE.
